INTERNAL EXPANSION PIPE WRENCH

Julius R. Oravetz, New York, N. Y.

Application August 2, 1946, Serial No. 688,023

2 Claims. (Cl. 81—72)

2

This invention relates to pipe wrenches and is directed more particularly to a wrench which may be inserted into a pipe nipple, spud or other threaded connection or fitting, and, when operated, will grip the interior surface thereof in order to allow such pipe or fitting to be screwed on or removed from an adjacent part of a piping system.

The primary object of the invention is to provide a simple, efficient and rugged construction, all parts of which are normally maintained in assembled relation and which, in use, will grip the pipe or fitting firmly, without serious damage thereto particularly if engaged with the threads of the pipe or fitting.

A further object of the invention is to provide a wrench which will operate within fittings and connections of widely varying sizes without requiring any change in the parts of the wrench or the substitution of any parts, and beyond which scope of sizes, parts of other size may be substituted in the wrench to adapt it to cooperate therewith.

Another object of the invention is to so construct an internal wrench that it may be operated either to connect or disconnect pipe fittings or connections, i. e., to impart rotation to such fittings or connections in either clockwise or counterclockwise directions, as may be desired.

Speaking generally, the wrench of this invention comprises a spindle, one end of which has an appropriate handle, while near its other end, said spindle is provided with a cam rigid with the spindle and extending longitudinally thereof. At the opposite ends of the cam, links are pivoted intermediate their ends to the spindle and carry at their ends pivoted arcuate jaws. The interior surfaces of the jaws are arcuate to coact with the cam for the purpose of spreading the jaws, and their external, arcuately shaped surfaces are serrated, so that they may be brought into contact with the interior of a pipe or fitting and forced to a firm grip therewith by the cam when the spindle is turned.

The jaws are pivoted to the links adjacent one longitudinal edge of each jaw, i. e., their leading edges, and the free edges, i. e., their trailing edges, are forced outwardly through the operation of the cam, so that relatively little movement of the cam will bring about relatively great movement of the jaws. By this construction the wrench is adapted to cooperate with pipe diameters of widely varying sizes.

The jaws are removably mounted on the links, so as to permit them to be reversed when it is

desired to reverse the direction of operation of the wrench or to permit smaller or larger jaws to be substituted in the event the pipe sizes to be operated upon so require, all as more specifically set forth in the following detailed description.

Features of the invention, other than those adverted to, will be apparent from the hereinafter detailed description and appended claims, when read in conjunction with the accompanying drawings.

The accompanying drawings illustrate one practical embodiment of the invention, but the construction therein shown is to be understood as illustrative, only, and not as defining the limits of the invention.

Figure 1 is a perspective view showing a pipe wrench embodying the present invention.

Figure 2 is a transverse section through the head of the wrench showing certain parts in central section and others in elevation.

Figures 3 and 4 are sections on the line 3—3 of Figure 2 with the cooperating pipe or fitting shown in phantom.

In the accompanying drawings, 1 indicates the spindle of the wrench. Its handle end is squared for cooperation with a handle 2, provided with two square holes into which the squared end of the wrench is adapted to fit. One hole is preferably provided at one end of the handle, while the other hole 3 may be intermediate the ends, as shown in Figure 2. Either hole may be used, depending upon the leverage required, or, if great leverage is necessary, a length of pipe may be slipped over the handle 1 and used to increase the leverage as is commonly done in manipulating plumbers' wrenches.

The head end of the spindle 1 carries a cam 4 which may be integral with the stem or attached thereto in any suitable way, but it should be rigid with the spindle. The cam is of oval cross section and it is arranged symmetrically about the axis of the spindle 1 and coaxial therewith. Beyond the end of said cam is formed a boss 5 which constitutes, in effect, an extension of the spindle and terminates in a reduced coaxial threaded post 6.

Embracing the spindle back or inboard of the cam, is a link 7 and embracing the boss 5 at the opposite or outboard end of the cam is a similar link 8. These two links are freely rotatable about the axis of the spindle and extend cross-axially thereof. The link 7 is held against backing away from the cam by a pin 9 having a forced fit in a hole through the spindle, although a cotter pin may be used instead of the pin 9.

The link 7 carries near its opposite outer ends two jaw supporting pins 10. These pins are secured by a forced fit, threads, welding or otherwise, to the link 7 and they extend in parallel relation to each other and to the axis of the spindle, alongside of the cam and project into holes 11 provided therefor in the link 8, without attachment within said holes. A wing nut 12 is screwed on to the threaded post 6 and normally holds the link 8 against backing off the ends of said pins.

Mounted on the pins 10 intermediate the links 8 and 9 are two gripping jaws 14. These jaws are generally of arcuate cross section and of a length corresponding to the length of the cam. Each jaw is provided near its leading edge 14a with a longitudinal hole through which one of the pins 10 passes, while the trailing edges 14b of the jaws are free, so that the jaws may bodily swing on said pins 10 (see Figs. 3 and 4). The outer faces of the two jaws are roughened so that they may more readily grip a pipe or fitting. In the drawings they are shown as serrated at 15, although they may be knurled, knobbed, or otherwise provided with sharp edges or projections, well adapted for the gripping function.

As shown, the outer surfaces of said jaws are also provided with grooves 16, so that the wrench may be used in bushings, spuds, and the like, which frequently are provided with oppositely disposed internal ribs or projecting keys adapted to facilitate their removal. These channels are intended for cooperation with such ribs or keys and may either interlock directly therewith or provide sufficient clearance around the keys to permit the sharpened exterior surfaces of the jaws to directly grip the internal surface of the fitting which is to be inserted or removed.

The inner surfaces 17 of the jaws are of concave arcuate shape for cooperation with the cam 4 and through rotation of the cam, while the jaws remain relatively stationary, these jaws may be collapsed or spread. When the wrench is to be inserted into a pipe or fitting, the spindle is turned so as to permit the jaws to collapse or move toward one another, so that the parts occupy the position indicated in Figure 3. With the parts in this relation, the head of the wrench may be readily inserted into a pipe P, shown in phantom in Figure 3. If the jaws are then held stationary, while the spindle is rotated in, e. g., the clockwise direction indicated in Figure 4, the cam will act against the inner surfaces 17 of the jaws to swing them outwardly and into engagement with the pipe, as shown in Figure 4. After this has been accomplished, continued rotation of the wrench will cause the jaws to grip and rotate the pipe or other connection, as the case may be, and the greater the rotating pressure, the greater will be the grip on the pipe.

Thus when the wrench is in the operation of rotating the pipe to attach or detach the latter, the whole wrench bodily rotates with the pivoted edges of the jaws moving in advance or leading the remainders of the jaws, while the free edges of said jaws trail behind. Thus the pivoted edges of the jaws may be graphically referred to as the "leading edges," while the opposite edges of such jaws may be referred to as the "trailing edges."

In the drawings, the jaws are so positioned as to adapt them to grip and rotate the pipe or fitting in a counterclockwise direction, i. e., in a direction to unscrew a right hand thread.

Should it be desired to reverse this operation, i. e., to screw in a right hand thread, the wing nut 12 may be removed, the link 8 withdrawn and the jaws 15 slipped off of the pins 10, reversed and returned to the pins. If the link 8 and wing nut 12 are then replaced, the parts will be in condition for operation of the wrench in a counterclockwise direction.

By pivoting each of the jaws along its leading edge, relatively little movement of the cam will effect relatively great movement of the trailing edge of the jaw and consequently the wrench is adapted to operate within widely different diameters. In the event, however, that pipes of greater diameter are encountered, the jaws shown in the drawings may be removed by removing the wing nut and link 8 and larger or thicker jaws may be substituted in order to handle the larger diameters.

The wrench of this invention is extremely rugged. It will withstand tremendous strains without breakage and yet the parts are not in themselves heavy. They are, however, so disposed that, during the actual gripping and turning operation, the cam jams the jaws against the interior surface of the pipe and thereafter there is very little strain on the pins 10 or on any other part of the structure since then practically all the strain is taken by the spindle and its integral cam. At all other times, the links nevertheless hold the jaws in assembled relation with respect to the cam and spindle, so that they cannot inadvertently fall into a pipe and become lost or clog the pipe. Nevertheless these parts may be readily dismantled for the purposes stated when desired.

The foregoing detailed description sets forth the invention in its preferred practical form, but the invention is to be understood as fully commensurate with the appended claims.

Having thus fully described the invention, what I claim as new and desire to secure by Letters Patent is:

1. An internal pipe wrench comprising a spindle provided near one end with a cam, links pivoted to the spindle intermediate their ends at the opposite ends of the cam, parallel pins carried by and extending between said links, and gripping jaws with one longitudinal edge of each jaw pivoted on one of said pins and the other longitudinal edge being free, the inner face of each jaw being concave for cooperation with the cam and the outer face of each jaw being roughened for gripping engagement with a pipe.

2. An internal pipe wrench provided with a spindle, near one end of which is rigidly carried a cam of substantially oval cross section arranged longitudinally of the spindle and coaxially thereof, a link pivotally mounted coaxially of the spindle at each end of the cam and intermediate the ends of the links, means locking the link at one end of the cam against backing away from the cam and the link at the other end of the cam being locked against backing away from said last named end of the cam by a threaded member screwed on to the free end of the spindle, pins anchored in the link at said one end of the cam and extending parallel to one another and to the axis of the spindle to and through perforations in the link at the other end of the cam, and jaws pivotally supported on said pins between said links, with the inner surfaces of the jaws being concave to cooperate with the cam and the pipe engaging surfaces of the jaws be-

ing roughened to grip the interior surface of a pipe.
